OPERATING LEVER FOR A RATCHET WRENCH

Robert W. Vose, West Springfield, Mass., assignor to
Moore Drop Forging Company, Springfield, Mass., a
corporation of Massachusetts

Application February 19, 1959, Serial No. 54,682

Term of patent 14 years

(Cl. D54—15)

Fig. 1 is a top plan view of an operating lever for a ratchet wrench showing my new design;

Figs. 2, 3, 4 and 5 are cross-sectional views taken on lines II—II, III—III, IV—IV, and V—V, respectively, of Fig. 1;

Fig. 6 is a perspective of the lever; and

Fig. 7 is a section taken along line VII—VII of Fig. 1.

The fragmentary dotted line disclosure of a wrench ratchet handle is shown only for purposes of illustration.

I claim:

The ornamental design for an operating lever for a ratchet wrench, as shown and described.
